DISPLAY EASEL

Filed Nov. 10. 1925

Inventor:
George H. Ailes,
By Jas. C. Hobensmith
Attorney.

UNITED STATES PATENT OFFICE.

GEORGE H. AILES, OF PHILADELPHIA, PENNSYLVANIA.

DISPLAY EASEL.

Application filed November 10, 1925. Serial No. 68,061.

My invention relates to display easels, that is to say, to a device adapted to hold various articles in such positions as to display them effectively.

5 The object of my invention is to provide a novel and efficient form of display easel formed of bent wire which may be inexpensively constructed, which will be readily adjustable for supporting articles of various 10 shapes, which is provided with means for also supporting a tag containing prices or descriptive matter, and the parts of which are readily separable whereby the same may be packed so as to occupy relatively small 15 space.

The nature and characteristic features of my invention will be more readily understood from the following description, taken in connection with the accompanying drawings forming part hereof, in which:

20 Figure 1 is a perspective view of a display easel embodying the main features of my present invention;

25 Fig. 2 is a side elevation thereof, showing the same supporting an article, and a descriptive or price tag associated therewith;

Fig. 3 is a front elevation of one of the members of the easel; and

30 Fig. 4 is a plan view of the other member thereof.

Referring to the drawings, in the particular embodiment of my invention therein shown, the easel comprises two separable members, each formed of bent wire. One of the members, which may be termed the upright member, is of inverted U-shape in general contour, and has side portions 5 which are coiled as at 6, for a purpose to 35 be presently explained. Extending below the coiled portions 6 are portions 7 constituting legs, the lower ends of which are adapted to rest upon the surface on which the easel is placed. The leg portions 7 may, if desired, be provided with upturned portions 8 extending to points in proximity to the coils 6.

Extending across from the upper ends of the side portions 5 are portions 9, which 40 are preferably inclined slightly upward toward the center, where there is provided a coiled portion 10. The coiled portion 10 is preferably made with at least two complete convolutions, whereby a price tag or 45 the like may be supported by inserting the

lower end thereof in the convolutions of the coils 10 (see Fig. 2).

The other or lower member of the easel is also U-shaped in its general contour, having side portions 12, the free ends of which are 50 bent slightly upward, as at 13, so as to rest more firmly upon the surface on which the easel is placed. The front end of this member is also bent slightly upward, as at 14, and extending across between the front ends 55 of the bent up portions 14 is a horizontal bar 15.

In assembling the device for use, the side portions 12 of the lower member are inserted in the coils 6 of the upright member. The 60 internal diameter of the coils 6 is such that the side portions 12 of the lower member may be readily inserted therein, but they are of such dimensions that the proper angular relationship of the two members will be 65 maintained when the article which is to be displayed is mounted in place on the easel. The side portions 12 of the lower member are readily slidable in the coils 6, and the 70 lower member is thus slid inward in assembling the device, whereby the horizontal cross bar 15 of said lower member will be positioned the proper distance with respect to the upright member as may be required by 75 the shape or size of the particular article 80 to be displayed, whereupon said article may be placed on the projecting ledge thereby provided, and supported at its rear by the upper parts of the upright member, at such 85 inclination that the article will be placed in 90 a position to be readily viewed.

It will be seen that there is thus provided a relatively simple and inexpensive, yet attractive form of display easel in which the parts are readily separable whereby the same 95 may be packed flat for shipment or storage, which may be quickly and conveniently assembled when it is desired to use the same, which when so assembled will support the 100 article to be displayed in an effective position, and which is provided with means for supporting a descriptive or price tag in connection with the article displayed, whereby the device will be of considerable value for 105 merchandising purposes, particularly in connection with small commodities.

Having thus described the nature and characteristic features of my invention, what I claim as new and desire to secure by Letters Patent, is:

1. A display easel comprising two separable members formed of bent wire, one of said members being adapted to be placed in an upright position, said upright member being substantially U-shaped in general contour and having side portions provided with coils and leg portions extending below said coils, parts extending across between the upper ends of the side portions, and a lower member also substantially U-shaped in general contour having side portions slidably mounted in the coils in the side portions of the upright member, and a horizontal bar extending across between the front ends of the side portions of the lower member, the arrangement being such that the extension of the front end of the lower member may be varied by sliding the side portions thereof in the coils in the side portions of the upright member.

2. A display easel comprising two separable members formed of bent wire, one of said members being adapted to be placed in an upright position, said upright member being substantially U-shaped in general contour and having side portions provided with coils and leg portions extending below said coils, parts extending across between the upper ends of the side portions and provided with a coiled portion adapted to receive and support a tag, and a lower member also substantially U-shaped in general contour having side portions slidably mounted in the coils in the side portions of the upright member, and a horizontal bar extending across between the front ends of the side portions of the lower member, the arrangement being such that the extension of the front end of the lower member may be varied by sliding the side portions thereof in the coils in the side portions of the upright member.

3. A display easel comprising two separable members formed of bent wire, one of said members being adapted to be placed in an upright position, said upright member being substantially U-shaped in general contour and having side portions provided with coils and leg portions extending below said coils, parts extending across between the upper ends of the side portions and provided with a coiled portion adapted to receive and support a tag, and a lower member also substantially U-shaped in general contour having side portions slidably mounted in the coils in the side portions of the upright member, said side portions of said lower member having slightly upturned portions at the rear ends thereof, and a horizontal bar extending across between the front ends of the side portions of the lower member having slightly upturned portions at the rear ends thereof, and a horizontal bar extending across between the front ends of

the side portions of the lower member, the arrangement being such that the extension of the front end of the lower member may be varied by sliding the side portions thereof in the coils in the side portions of the upright member.

4. A display easel comprising two separable members formed of bent wire, one of said members being adapted to be placed in an upright position, said upright member being substantially U-shaped in general contour and having side portions provided with coils and leg portions extending below said coils, parts extending across between the upper ends of the side portions and provided with a coiled portion adapted to receive and support a tag, and a lower member also substantially U-shaped in general contour having side portions slidably mounted in the coils in the side portions of the upright member, said side portions of said lower member having slightly upturned portions at the front ends thereof, and a horizontal bar extending across between the front ends of said last mentioned upturned portions, the arrangement being such that the extension of the front end of the lower member may be varied by sliding the side portions thereof in the coils in the side portions of the upright member.

5. A display easel comprising two separable members formed of bent wire, one of said members being adapted to be placed in an upright position, said upright member being substantially U-shaped in general contour and having side portions provided with coils and leg portions extending below said coils, parts extending across between the upper ends of the side portions and provided with a coiled portion adapted to receive and support a tag, and a lower member also substantially U-shaped in general contour having side portions slidably mounted in the coils in the side portions of the upright member, said side portions of said lower member having slightly upturned portions at the rear ends thereof and having slightly upturned portions at the front ends thereof, and a horizontal bar extending across between the front ends of said last mentioned upturned portions, the arrangement being such that the extension of the front end of the lower member may be varied by sliding the side portions thereof in the coils in the side portions of the upright member.

In testimony whereof, I have hereunto signed my name.

GEORGE H. AILES.
